United States Patent Office

Des. 182,486
Patented Apr. 8, 1958

182,486

MITT

Jack W. Vinetz, Los Angeles, Calif.

Application January 18, 1957, Serial No. 44,524

Term of patent 7 years

(Cl. D3—11)

FIG. 1

FIG. 2.

I claim:

The ornamental design for a mitt, substantially as shown.
